UNITED STATES PATENT OFFICE.

GEORGE W. GOFF, OF EAST HAMPTON, CONNECTICUT, ASSIGNOR TO THE EAST HAMPTON BELL COMPANY, OF SAME PLACE.

DESIGN FOR A SLEIGH-BELL.

SPECIFICATION forming part of Design No. 12,563, dated November 1, 1881.

Application filed August 29, 1881. Term of patent 7 years.

To all whom it may concern:

Be it known that I, GEORGE W. GOFF, of East Hampton, in the county of Middlesex and State of Connecticut, have invented a new 5 Design for a Sleigh-Bell; and I do hereby declare the following, when taken in connection with the accompanying drawing and the letters of reference marked thereon, to be a full, clear, and exact description of the same, and which 10 said drawing constitutes part of this specification, and represents a side view.

This invention relates to a design for the class of bells commonly called "sleigh-bells"—that is to say, bells which consist of a hollow 15 shell, within which a loose ball is placed, and usually attached to straps; and the design consists in the configuration of the bell as shown in the accompanying illustration.

The upper part, A, of the bell is in outline 20 the shape of an open-mouthed bell, or what is commonly called "bell shape." The lower part,

B, is of inverted-bell shape, but longer than the upper section, A—that is to say, the upper and lower end of the bell are rounded—thence gradually expanding from each end 25 turn suddenly outward to form a sharp rib-like projection between the two sections, the upper section being about half the length of the lower, as shown in the accompanying illustration.

I claim—

The design for sleigh-bell, consisting of the upper section, A, of bell shape, and the lower section, B, of inverted-bell shape, but longer than the upper section, the two sections meeting 35 to form a projecting rib, as shown in the accompanying illustration.

GEORGE W. GOFF.
